DESIGN FOR A BOTTLE

Frank T. Kessler, Philadelphia, Pa.

Application December 19, 1933, Serial No. 50,113

Term of patent 14 years

To all whom it may concern:

Be it known that I, FRANK T. KESSLER, a citizen of the United States, residing at Philadelphia, in the county of Philadelphia and State of Pennsylvania, have invented a certain new, original, and ornamental Design for a Bottle, of which the following is a specification, reference being had to the accompanying drawings, forming part thereof.

Figure 1 represents a front elevational view of the design for bottle embodying my invention, shown somewhat in perspective at a slight angle from above.

Figure 2 represents a rear elevational view of the design for bottle embodying my invention, shown somewhat in perspective at a slight angle from above.

Figure 3 represents a side elevational view of the design for bottle embodying my invention, shown somewhat in perspective at a slight angle from above.

Figure 4 represents a top plan view of the design for bottle embodying my invention.

I claim:

The ornamental design for a bottle, as shown.
FRANK T. KESSLER.
